UNITED STATES PATENT OFFICE.

CHARLES A. BUERK AND JEAN DUTEY, OF CHICAGO, ILLINOIS.

FIRE EXTINGUISHER.

Application filed January 18, 1926. Serial No. 81,910.

This invention relates to a fire extinguisher of the portable type, and is distinguished from the fire extinguishers now in use by reason of the fact that it is provided with at least two chambers, one of which is designed to hold and dispense dry powder, while the other chamber is designed to hold and dispense a liquid. The principal object of the invention is, therefore, to provide a unitary and complete extinguisher of this kind, in which both liquid and powder may be discharged at the same, and in different places, at the same, or different times.

Fire extinguishers using dry powder as an extinguishing agent are known to be highly effective and efficient. Flames are killed by being instantly smothered, which makes such apparatus incomparable for use on incipient fires of all kinds and especially extra hazardous fires, such as gasoline, oil, all inflammable liquids, and electric fires.

On fires known as class "A" fires (Underwriters' Laboratory Classification) on which the quenching and cooling effect of a liquid is of first importance, that is fires in ordinary combustible materials, such as wood, excelsior, rubbish, etc., powder is unable, most of the time, to kill the embers which in time might cause a reignition.

The present invention provides, in the same apparatus, a dry powder device and a liquid extinguishing device, so that, whenever necessary, the smothering effect of the extinguishing powder can be completed by the wetting and cooling effect of the liquid employed, or vice versa. The liquid employed may be water, carbon tetrachloride, anti-freeze solution, or whatever liquid is best suited for the situation.

Referring more particularly to the drawings, Figure 1 is an elevation, partly in section, showing a fire extinguisher constructed in accordance with the principles of this invention; and Figure 2 is a sectional detail, illustrating how the pressure cylinder may be divided into two separate cylinders and supported by the container.

In its preferred form, the present invention comprises a substantially conical shell 1 at the apex of which is a fixed discharge nozzle 2, held in place by a collar 3 and removable for the purpose of filling this end of the container. The base of the receptacle is closed, and has a filling cap 4 in which is a check or safety valve 5 with a protecting and supporting stand 6 projecting therefrom, by

means of which the fire extinguisher may be supported and may be handled or held while in operation.

Intermediate the ends of the receptacle, 60 and preferably nearer the base, is a cross partition 7 which divides the receptacle into a base chamber and the apex chamber, the latter also being provided with a check or safety valve 8. Connected through the outer side of the receptacle, and communicating with the said chambers are tubular fittings 9 and 10, the one in the apex chamber having a spray nozzle 11 adapting it to be used for powder. From the base chamber, a tubular member 12 extends, to which is connected a flexible hose 13 with a nozzle 14 at the end thereof.

Pressure may be applied to the separate chamber of the extinguisher in any desired or suitable manner through the fittings 9 and 10. They may be connected with any suitable source of air or pressure supply; but for portable use, it is desirable to have a portable pressure source as well. For this purpose, a small cylinder 15, capable of withstanding 80 high pressure is provided at the ends with valve fittings 16 and 17 which are connected to the tubular fittings 9 and 10 by suitable couplings 18. Instead of having one cylinder 15 two similar cylinders 19 may be applied 85 to the chambers as described, and the adjacent ends of these cylinders may be supported and attached to the receptacle 1 by means of a tubular bracket 20 supported at the side of the receptacle 1 as shown more clearly in 90 Figure 2.

With this construction, it is obvious that either or both of the chambers may be caused to discharge their contents separately by opening or closing the valves 16 and 17, and 95 with a flexible hose for one of the chambers, the contents thereof may be discharged in a different direction than that from the first nozzle 2. The flames may be smothered by the powder, and the embers, which are dangerous, may be wet down with the liquid from the other chamber. The fluid under pressure in the cylinder or cylinders may be air, CO₂, or any suitable fluid, the pressure being sufficient to completely expel all the 105 contents of both of the chambers of the extinguisher.

We claim:

1. A portable fire extinguisher in the form of an inverted cone having a transverse partition therein dividing it into compartments, pressure holding means having a separate 110

valved connection with each compartment, tubular discharging means leading from each compartment, and a flexible hose in connection with one of the tubular means which enables the discharge from one of said compartments to be directed in the same direction as that from the other compartment or in a different direction.

2. A portable conical fire extinguisher having a fixed discharge nozzle at the apex and an interior partition forming separate closed chambers one of which is for liquid, pressure holding means having individual valved connections with the chambers, and a tubular connection from the chamber at the base including a flexible hose for directing the contents thereof at will with the said fixed nozzle and away from it.

3. A portable fire extinguisher having closed pressure compartments for powder and liquid, valved pressure holding means communicating with said compartments for separately and simultaneously expelling the contents of the compartments, means for directing the contents of said compartments at will in the same and in different directions, and separate safety valves for each of the compartments.

4. A portable fire extinguisher having a conical shell with an interior partition to form a truncated conical base compartment and with a fixed discharge nozzle at the apex of the shell, pressure holding means having separate valved connections with each of the compartments, and a flexible discharge hose for the base compartment which enables the discharge from said compartment to be directed in the same direction as that from the other compartment or in a different direction.

5. A portable fire extinguisher having closed pressure compartments in the same

container, pressure holding means comprising a separate valved cylinder for each compartment, and discharge means for directing the contents of the compartments at will in 45 the same and different places.

6. A portable fire extinguisher comprising a receptacle with a partition forming separate compartments, discharge means therefor, pressure holding means comprising a separate valved container for each compartment and arranged in line at the side of the receptacle, and means common to the containers attached to the receptacle for holding the containers in alignment.

7. In a fire extinguisher, means forming separate compartments, pressure holding cylinders having valved connections for attaching them individually to the compartments, and common means attached to the said compartment forming means to extend over the adjacent ends of the cylinders when they are in alignment to protect them and hold them in such position.

8. A portable fire extinguisher comprising a conical vessel with a partition near the base thereof adapted to form two separate closed compartments the one near the apex for containing powder and the other compartment for containing liquid, the extinguisher being held with the cone in an inverted position, a fixed nozzle at the apex of the cone pressure applying means having separate valve connections with each of the compartments, means attached to the outer wall of the extinguisher having a cylindrical portion for holding pressure containers therein, a flexible hose extending from the liquid compartment, and separate pressure relief valves for the compartments.
